(57) **CLAIM**

The ornamental design for a combined pet carrying and backpacking backpack, as shown and described herein.

DESCRIPTION

FIG. 1 is a perspective view of a combined pet carrying and backpacking backpack in accordance with our invention;

FIG. 2 is a left-side view thereof;

FIG. 3 is a right-side view thereof;

FIG. 4 is a rear view thereof;

FIG. 5 is a front view thereof;

FIG. 6 is a top view thereof;

FIG. 7 is a bottom view thereof; and,

FIG. 8 is a perspective view of the combined pet carrying and backpacking backpack showing one exemplary environment of use.

The broken line rectangles shown in FIGS. 1 and 4, and partially shown in FIG. 8, as well as the broken lines showing a clip-on bag in FIG. 8 indicate portions of the combined pet carrying and backpacking backpack that form no part of the claimed design. The broken line u-shaped features with rectangles therein shown in FIG. 5 indicate portions of the combined pet carrying and backpacking backpack that form no part of the claimed design. The broken line cords and associated cord locks shown in FIGS. 1-8 indicate portions of the combined pet carrying and backpacking backpack that form no part of the claimed design. The broken lines adjacent to other parts shown in the design indicate stitching that forms part of the claimed design.
